UNITED STATES PATENT OFFICE.

ROBERT ROBINSON, OF MCKEES ROCKS, PENNSYLVANIA.

SANDING DEVICE.

1,326,140.

Specification of Letters Patent. Patented Dec. 23, 1919.

Application filed February 28, 1919. Serial No. 279,902.

To all whom it may concern:

Be it known that I, ROBERT ROBINSON, a citizen of the United States of America, residing at McKees Rocks, in the county of Allegheny and State of Pennsylvania, have invented certain new and useful Improvements in Sanding Devices, of which the following is a specification.

This invention relates to sanding devices, 10 designed primarily for use in connection with railway locomotives, but it is to be understood that a sanding device in accordance with this invention can be employed for any purposes wherein it is found applicable, and the invention has for its object to provide, in a manner as hereinafter set forth, a sanding device having means whereby the sand is deposited on the track rail in very close proximity to the point where 20 the tread of the wheel contacts with the head of the rail, under such circumstances the wheel engages the sand almost immediately after it is deposited on the track rail and skidding or slipping action is reduced to a 25 minimum, furthermore waste of sand is prevented as the wheel contacts therewith before the sand is blown away.

Further objects of the invention are to provide a sanding device which is simple in 30 its construction and arrangement, strong, durable, efficient in its use, having means to maintain it and to restore it in and to normal position in case the discharge nozzle is shifted by an obstruction at or near the 35 track, readily set up in operative position, and comparatively inexpensive.

With the foregoing and other objects in view the invention consists of the novel construction, combination and arrangement of 40 parts as hereinafter more specifically described and illustrated in the accompanying drawings, wherein is shown an embodiment of the invention, but it is to be understood that changes, variations and modifications 45 can be resorted to which come within the scope of the claims hereunto appended.

In the drawings wherein like reference characters denote corresponding parts throughout the several views:—

50 Figure 1, is a side elevation, broken away, of a locomotive showing the adaptation thereto of a sanding device in accordance with this invention.

Fig. 2, is a sectional detail illustrating the 55 discharge nozzle.

By way of example the sanding device is

illustrated in connection with a railway locomotive 1 and which is provided with a sand box 2. The wheels of the locomotive are indicated at 3, 4. 60

Leading from the sand box 2 is a sand delivery pipe 5 which extends to a point above the track rail 6, and extending from the pipe 5 is a sand delivery pipe 7, which terminates at a point above the track rail 6. 65

The pipe 5 is arranged at the front of and in close proximity to the wheel 3, and the pipe 7 extends rearwardly and is curved around the wheel 4 in close proximity thereto. The pipes 3, 4 are of metal and terminate at a point above the track rail so they cannot be damaged or injured by any rigging, obstruction, or elements of a switch or a frog. 70

The pipe 3, as well as the pipe 4, has attached to the lower end thereof a flexible discharge nozzle 8, and as the construction of each nozzle is the same, but one will be described, the description of one applying to the other. 75

The nozzle 8 is formed from a flexible body, preferably rubber, and is secured to the lower end of the delivery pipe by a clamp 8^a. The lower edge of the nozzle 8 is flat throughout and directly opposes and 85 is positioned in very close proximity to the tread of the track rail 6, as well as in very close proximity to that wheel of the locomotive with which the nozzle co-operates. 80

The nozzle 8 is disposed at an inclination 90 and extends toward that wheel with which it co-operates, and arranged, as well as being secured, within the nozzle 8 is a coiled spring 9, conforming in contour to the shape of and substantially of a length equal to the 95 length of the nozzle, as well as engaging the inner face of the nozzle.

The flexibility of the nozzle prevents the breakage or permanent bending thereof when meeting with an obstruction and the 100 spring 9, not only maintains the nozzle 8 in normal position, so as to deliver the sand at a point in close proximity where the wheel engages with the track rail, but also restores the nozzle to normal position in 105 case the nozzle is shifted to one side when meeting with an obstruction.

By the employment of the nozzle as shown the sand is deposited upon the track rail at a point where it can be immediately engaged by the tread of the wheel under such condition reducing skidding or slipping of 110

the wheel to a minimum, furthermore saving in sand is obtained as the latter is engaged by the wheel before the sand can be blown off the track rail.

5. What I claim is:—

1. A sanding device comprising a delivery pipe, a flexible discharge nozzle secured to the lower end of said pipe and extending toward a track rail and a wheel traveling thereon, and a coiled spring arranged within and permanently engaging said nozzle and of a length substantially equal to the length of the nozzle and providing means for maintaining the nozzle in normal position.
10. 2. In sanding devices a flexible discharge nozzle adapted to be arranged in close proximity to a track rail, said nozzle having its lower edge flat throughout and directly opposing throughout the tread of the track rail, and a coiled spring arranged within and permanently engaging the inner face of said nozzle and of a length substantially equal to the length of the nozzle.
15. 3. In a sanding device a sand delivery pipe, a flexible nozzle mounted on and extended from the lower end of said pipe, a clamp for securing the upper end of the nozzle on the lower end of the pipe, and a coiled spring arranged within and permanently engaging the inner face of said nozzle and extending from the lower end thereof to the lower end of said pipe.
20. 4. A sanding device comprising a delivery pipe, a flexible nozzle mounted on and extended from the lower end of said pipe, said nozzle having a flat lower edge adapted to be positioned in very close proximity to the tread of a track rail and in close proximity to the wheel traveling on the rail, a clamp for securing the upper end of the nozzle on the lower end of said pipe, and a coiled spring arranged within and snugly fitting said nozzle and extending from the lower end of the latter to the lower end of said pipe.

In testimony whereof I affix my signature.
ROBERT ROBINSON.
